UNITED STATES PATENT OFFICE

2,624,983

GRINDING DEVICE FOR LAWN MOWERS

Oscar C. Rink, Liberty, Mo.

Application April 27, 1950, Serial No. 158,367

4 Claims. (Cl. 51—48)

1

This invention relates to a grinding machine for the blades of lawn mowers, and more particularly to a grinding machine adapted to sharpen the blades of lawn and power mowers without removing the blades therefrom.

The principal object of the present invention is to provide a clamping member on the grinding machine for mounting the mower in its entirety thereon so that a grinding wheel of the machine may contact the blades and be moved thereacross without removing the blades from the mower.

Other objects of the invention are to provide a support including a platform upon which the clamping member is mounted and a rotatable frame on said support carrying the grinding wheel which is manually slideable across the rotatable frame when the grinding wheel is in contact with the blade; to provide for adjustable mounting of the grinding wheel with respect to the blades of the mower when the mower is held on the support by the clamping member; to provide a platform on the support so it may slide thereon to adjust the grinding wheel with respect to the blades on mowers of different size; to provide a second clamping member on the end of the platform opposite the first clamping member for mounting the stationary blade of the mower; to provide means on the frame for rotating the same on the platform for positioning the grinding member for sharpening the horizontal blade; to provide means on the frame for adjusting the grinding wheel with respect to the blade being sharpened; to provide a track on the frame for movement of the grinding wheel mechanism thereacross; to provide roller mounting of the motor on said track; to provide means on the frame for adjustment of the grinding wheel relatively to the blade by movement of the grinding wheel on an axis with the shaft on which the motor is mounted; to provide a device of this character easily knocked down and packed for shipment in a compact condition, and to provide a device of this character simple, economical to manufacture and efficient in operation.

In accomplishing these and other objects of the invention, I have provided improved structure, the preferred forms of which are shown in the accompanying drawings, wherein:

Fig. 1 is a perspective view of a grinding machine embodying the features of the invention.

Fig. 2 is a vertical sectional view through a part of the machine showing the mower mounted on the clamping member and the grinding wheel in contact with a blade of the mower.

Fig. 3 is a top plan view of the machine with parts broken away to better illustrate the invention.

2

Fig. 4 is an elevational view partly in section particularly showing the motor and motor mounting frame.

Fig. 5 is a cross section through a part of the frame particularly illustrating the eccentric arrangement for adjustment of the grinding member to the blade.

Fig. 6 is an elevational view partly in section showing the adjusting mechanism of the grinding wheel to the blade.

Referring more in detail to the drawings:

1 designates a grinding machine embodying the features of the present invention and comprising a tubular standard 2 having a plurality of removable feet 3 clamped to the lower portion thereof by bolts 5 and provided with a cap plate 6 secured thereto, as by welding, and forming a base or support for a platform 7. The platform 7 is preferably a casting having end portions 8 and 9 and sides 10 and 11 being connected by a central horizontal web 12. Plate 6 and web 12 are provided with aligning apertures through which bolts 13 are applied to secure the platform 1 to the standard 2. A pair of braces 14 and 15 are provided on each side of the standard and secured thereto by a bolt 16 the other ends of the braces being secured to the respective sides 10 and 11 of the platform near the ends 8 and 9 by bolts 17 and 18 to form a rigid structure.

30 A frame structure 19 is slidably and rotatably mounted on the platform 7. A plate 20 having depending flanges 21 and 22 near its respective ends is provided for movement across the top of the platform 7. Guide rails 23 and 24 are welded to the inner side of the depending sides 10 and 11 near the top thereof and a plate 25 having upstanding pins 26 is adapted to slide beneath the guide rails and longitudinally thereof. A plate 28 is welded to the plate 20 and a plate 29 is welded to the underneath side substantially near the center of a base member 30 of the frame 19. The base member 30, plates 29, 28 and 20 are centrally bored and the plate 25 is also centrally bored and threaded for receiving the threaded end 31 of a bolt 32 which holds the frame 19 to the platform 7. By loosening the bolt 32 the frame may be moved longitudinally of the platform 7 as desired.

50 The base member 30 of the frame is an inverted channel and the flanges thereof are connected by a web 33 for stiffening the channel. Mounted on the respective ends of the base member are trunnions 34 for arms 35 and 36, the trunnions extending into openings in the respective ends 55 of the arms, the arms being provided with slots 37 for a purpose later described. The arms 35 and 36 have enlarged lower ends as indicated at

38 and spaced from the openings for the trunnions are openings 39 into which the respective ends of a tube 40 are pressed and held rigidly to the arms. The tube 40 forms a trackway for mounting of a motor 41 and a grinding wheel 42 thereon also later described.

The motor 41 is provided with a base plate 43 adapted to be secured to a carriage plate 45 by bolts or the like 46. The plate 45 is provided with a depending base lug 47, the lug 47 being provided with spaced threaded openings that are angularly directed on the underneath side thereof to receive the threaded shanks of stud bolts 48 and 49. Mounted on the stud bolts 48 and 49 are rollers 50 and 51 spaced so that they engage the respective upper sides of the tubular trackway 40 for movement of the motor across the framework structure.

An arm 52 projects from the motor carriage plate 45 for mounting of the grinding wheel 42 thereon. The inner end of the arm 52 is provided with a slot 53 forming a fork for engaging over the carriage plate as best illustrated in Fig. 6, and is secured thereto by bolts 53'. The outer end of the arm 52 is provided with a head 54 consisting of a housing 55 provided with openings near the lower edge thereof adapted to receive a shaft 56 of grinding wheel 42. The housing 55 is removably mounted on the arm by cap screws 57 and 58', the arm 52 being provided with a depending portion 59 having a bore opening in which a cap screw 58 extends. The extension 60 of the arm 52 is provided with openings adapted to receive the cap screws 57 and 58' to hold the upper end of the housing rigidly to the arm. Integrally formed with the arm 59 and the arm 52 is a brace 61 to lend rigidity to the arm structure. The front portion 63 of the housing for the grinding wheel is provided with a threaded opening adapted to receive a cap screw 64 for mounting of the eye shield 65 thereon.

The housing 55 has an extension on one side providing a housing 67 for a pulley 68 mounted on the shaft 56 and held thereon by the usual set screw (not shown). The motor 41 is provided with the usual shaft 69 upon which is mounted a pulley 70 and a belt 71 runs over the pulleys 68 and 70 for rotating the grinding wheel 42 upon operation of the motor.

The outer ends of the arms 35 and 36 are provided with openings 72 in which are rotatably mounted short shafts 73 having eccentric longitudinal bores 74 adapted to receive pins 75. A tubular member 76 extends between the outer ends of the arms 35 and 36 in alignment with the pins 75. Mounted within the ends of the tubular member 76 are couplers 77 threadedly bored at each end and a rod 78 provided with threads 79 on each end engages in the inner threaded bores of the coupling members 77. The pins 75 have their ends threaded, the inner ends thereof engaging in the outer threaded bores of the coupling members 77 and their outer ends are provided with nuts 79', as best illustrated in Fig. 5. Washers 80 are provided on the pins 75 between the tubular member 76 and the arms 35 and 36. A collar 81 surrounds the tubular member 76 adjacent the arm 35 and has a threaded opening adapted to receive a set screw 82 for holding the collar thereon. Secured to the collar opposite the set screw by welding or the like is a rod 83 adapted to engage in an opening 84 of a pin 85 rigidly secured in an opening 86 in the arm 35 spaced from the end 75

of the arm as best illustrated in Fig. 5, the rod 83 acting as a guide, as later will be described.

The tubular member 76 is provided with a threaded opening 87 near the center thereof adapted to receive a screw 88 to provide a bend or slight arc in the member 76 to adjust the grinding wheel to the reel of the mower upon which the blades are mounted which will later appear. Each of the short shafts 73 is laterally bored and provided with threads as indicated at 89 for receiving a threaded end of a rod 90 having head 91 for movement of the short shaft to provide for eccentric adjustment of the rod.

Mounted on the respective ends 8 and 9 of the platform near the lower portion thereof are clamping devices 92 and 93. As these clamping devices are substantially identical, only one will be described. A plate 94 is secured to the end 9 of the platform by bolts 95 and 96 and formed integral with the plate member are outwardly extending base arms 97 and 98 having notches 99 and 100 in their upward edges forming lower jaws. Extending upwardly near the plate 94 on each arm are ears 101 to which are pivotally mounted by bolts or the like 102, jaws 103 and 104 extending vertically above the lower jaws 97 and 98. The lower jaws are provided with an opening near the outer end for pivotally mounting, by means of bolts 105, clevises 106 and 107. The outer end of the clevises are threadedly bored and provided with set screws 108 and 109 respectively.

110 designates the axle of a mower having wheels 111 carrying a frame 112 upon which is mounted a reel 113 having a plurality of spiral blades 114. The frame also carries a stationary blade 115 running parallel with the axis of the reel and secured to a stiffening bracket 115' which is the usual practice and the blade 115 is provided with a sharp edge as indicated at 116. 117 designates a roller at the rear of the mower is also the usual practice.

When mounting the mower on the clamping device 92 the axle 110 is placed in the notches 99 and 100 of the arms 97 and 98 and the upper jaws 103 and 104 engage the upper part of the axle and are tightened thereon by the set screws 108 and 109 in the clevises 106 and 107 in a position shown in Fig. 2, so that the grinding wheel 42 will engage one of the blades 114. The frame 119 is adjusted with respect to the platform by loosening the bolt 32 so that the grinding wheel will contact the blades of the mower at substantially the right position, the adjustability of the frame on the platform being adapted for fitting of the grinder to mowers of different size.

The side 118 of the housing 55 on the outer end of the arm 52 is provided with a guide plate 119 pivotally mounted thereon by bolt or pin 120, the lower end of the guide being provided with a shoulder 121 to contact the edge of the blade 114 to guide the grinding wheel thereacross when the device is in use.

Further adjustment of the grinding wheel to the blades 114 is provided by a gauge member 122 adapted to engage over the tubular member 76 adjacent the motor 41. The gauge 122 consists of an arm 123 secured to the arm 52 adjacent the head thereof by a bolt 124. The arm 122 comprises a frame having a short arm 125 and a cross member 126, the cross member being centrally and threadedly bored as at 126', and adapted to receive a threaded shank 127 of a pin having a head 128. The inner end of the threaded pin 127 is rotatably secured to a guide member 130 being notched at its end, as indicated

at 131, to slidably engage the respective arms 123 and 125 of the gauge, the guide member 130 being bored to receive the annular grooved end 132 of the pin which is held in the bore opening by pin 133. The opposite side of the guide 130 is provided with a recess 136 in which is mounted, by pin or the like, a roller 137 adapted to engage against the tubular member 76 mounted on the outer end of the arms 35 and 36 of the frame. To keep the pin 127 from turning under vibration, a guide member 138 being centrally bored and provided with threads and having its ends slotted for sliding engagement on the arms 123 and 125, is located adjacent the end 126 and a compression spring 139 is provided therebetween urging the guide 138 away from the cross member 126, thus holding the threads of pin 127 under tension and preventing it from turning inadvertently. The arm 122 is pivotally mounted by the bolt 124 to the arm 52 for operation of the threaded pin 127 to exert downward pressure on the tubular member 76 which will raise the head 54 on the outer end of the arm 52 thereby raising the grinding wheel 42 to adjust the same with respect to the blades 114 of the mower. The turning of the pin 127 in the opposite direction or in anti-clockwise direction will cause the arm to be lowered, thus lowering the grinding wheel 42 with respect to the blade 114.

For sharpening of the stationary blade 115 is a frame 140 comprising spaced arms 141 and 142 provided with openings near the respective ends adapted to receive the ends of rod 143 and 144, the ends of the rod 143 providing trunnions upon which the arms 141 and 142 are mounted. The rod 143 is clamped by the jaws 97 and 98 and 163 and 164 respectively and held securely therein by tightening of the screws 108 and 109 in the clevises 106 and 107. Slots 145 and 146 are provided in the respective ends of the arms 141 and 142 and set screws 147 and 148 and adapted to engage the threaded lateral openings in the ends of the arms 141 and 142 for retaining the rods 143 and 144 therein. The plate 150 which engages over the top of the rod 144 is tack welded thereto. A pair of clamping members 151 and 152 is provided for holding the blade 115 on the plate 150, the clamping members having flanges 153 depending from outer edges thereof and provided with threaded bores 154 adapted to receive the threaded ends 155 of locking pins 156 having heads 157. The opposite ends of the clamping members are provided with inwardly extending flanges adapted to engage the underneath side of the plate 150 as indicated at 159 (Fig. 2). Tightening of the locking pin on the plate 150 will hold the clamping member in the desired place to accommodate the stationary blade of different lengths.

In order to mount the stationary blade for sharpening on the framework structure each of the clamping members 151 and 152 is provided with a web 160, and attached by welding or other suitable means to the outer side of the web is a tubular member 161 in which extends a pin 162 having its upper end turned to form a hook 163, the other end being threaded to accommodate a thumb nut 164 for holding the blade 115 on the framework structure.

In order to provide rotation of the frame 19 on the platform 7 a bracket 167 is pivotally mounted to the forward side 168 of the channel member 30 with its lower end extending below the plate 23 and engages against a set screw 170 providing a stop for the frame 19 with respect to

the platform. When it is desired to rotate the frame the bracket is turned so that its fore end will rise above the stop so that the device may be rotated. The frame 19 may be turned to 180 degrees and stopped by a set screw 171 is provided on the plate 20. The set screws 170 and 171 extend through threaded openings in pins 172 and 173 respectively and their inner ends will engage against the lower end of the bracket 167 to lock the bracket in place and also to provide proper alignment of the frame with the grinding wheel 42.

In operation of a device constructed and assembled as described, the axle of the mower is mounted in the clamping devices 92 and 93 and the frame 19 is slidably adjusted on the platform 7 so that the grinding wheel 42 carried on the frame is substantially in alignment with one of the blades 114 on the reel of the mower.

The arms 35 and 36 have slots in their lower ends intersecting the openings in which the trunnions engage for mounting of the arms having downwardly extending jaws. One of the said jaws is provided with a threaded bore and the other a bore through which a cap screw 37' extends and engages in the threaded bore opening for clamping the arms on the trunnions. After the frame is adjusted on the platform, the cap screws 37' are loosened so that the arms may be adjusted to raise or lower the grinding wheel with respect to the blade, and then the cap screws are tightened.

The motor with its grinding wheel arm is then moved laterally so that the grinding wheel 42 is substantially adjacent one end of the blade, then the gauge 122 is adjusted for movement of the grinding wheel relative to the frame structure in order that the grinding wheel may contact said end of the blade. The upper ends of the arms 35 and 36 are slotted as at 72' and provided with cap screws 73' to form a movable friction grip, to provide for movement of the short shafts 73 in said arms without readjustment of the threaded pins 90. Further adjustment of the grinding wheel to the blade may be accomplished by manipulation of the pin 90 to provide the proper alignment of the tubular member 76 with respect to the axis of the reel of the mower. The grinding wheel is then moved across to the opposite end of the blade and the pin 90 in that end of the eccentric mechanism adjusted to provide a more accurate alignment of the grinding wheel with respect to the blade.

In some instances, it may be desirable to provide for a higher grinding of the center of the blade than the respective ends. In order to accomplish this type of grinding, the set screw 88 is adjusted in the threaded bore 87 in the tubular member 76 in order to provide a bend or slight arc in the member 76 which guides movement of the grinding wheel with respect to the blade of the reel as it moves thereacross, the set screw 88 bearing against the rod 78 to accomplish this purpose.

After the proper adjustments have been made as above described, the grinding wheel is moved across the blade by a manual movement, the guide member 119 with its shoulder 121 engaging the blade. As the wheel is moved thereacross the reel will be turned so that the blade will be in alignment with the wheel at all times. The rotation of the grinding wheel in an anti-clockwise direction (Fig. 2) will exert a slight pressure against the blade to hold the blade in contact with the shoulder of the guide member. If fur-

ther sharpening of each blade is necessary, the threaded pin 127 may be turned by handle 128 to lower the grinding wheel with respect to the blade to accomplish further cutting of the blade.

Some mowers may include certain obstructions and in order to accommodate for such exigencies, I have provided a cutout portion 174 in the end 9 and side 11 of the platform, as illustrated in Figs. 1 and 2.

When it is desired to sharpen the stationary blade 115, it is removed from the frame of the mower and fastened on the clamping members 151 and 152 by placing it on the webs 160 and engaging the upper portion of the end thereof by hooks 163. The nuts 164 are tightened to hold the blade securely in place. The bolt 32 of the frame is then loosened and the bracket 167 is rotated to disengagement from the stop member so that the frame 19 may be rotated upon the platform 7 to 180°, or so that the grinding wheel will be adjacent to the stationary blade. The bracket is then rotated so that it is lowered and will engage against the set screw 171. The frame 19 is then adjusted on the platform to proper alignment of the grinding wheel with the cutting edge of the blade and the same adjustments made of the arms 35 and 36, gauge member 122 and eccentric mechanism as above described.

It will be obvious from the foregoing that I have provided an improved grinding machine for the blades of lawn mowers and which has novel clamping means for holding the mower on the device and for adjustment of the grinding wheel at various positions with respect to the blades without removing the reel from the mower, and also for sharpening of the stationary blade of the mower by rotation of the frame and its cutting wheel with respect to the platform and supporting member.

What I claim and desire to secure by Letters Patent is:

1. A machine of the character described including a support, a substantially horizontal platform on the upper end of the support, spaced guides extending across the platform, a carrier member movable along the guides, work supports on the platform at opposite ends of the guides, a frame, a guide rail carried by the frame transversely of the guides on the platform, a motor carriage movable along the guide rail, an arm projecting from the motor carriage for supporting a motor driven tool above one of the work supports, a complementary guide rail carried by the frame in spaced parallel relation with the first named guide rail, a gauge member movable along the complementary guide rail and having connection with said arm whereby the complementary guide rail cooperates with the first named guide rail in supporting the grinding wheel relatively to said work support, and means rotatably mounting said frame on the carrier for turning the frame on said carrier to position the grinding wheel over the other of said work supports.

2. A machine of the character described including a support, a substantially horizontal platform on the upper end of the support, a work support on the platform, a frame having adjustable support on the platform and including laterally spaced brackets, a guide rail having ends carried by the brackets, a tubular rail member, eccentrics supporting ends of the tubular rail member on the brackets, a rod extending coaxially within the tubular rail member and having ends connecting the eccentrics, a setscrew carried by the tubular rail member and

having its inner end bearing upon the rod to curve the tubular rail member, a carriage having movable support on the guide rail and the tubular rail member, and a tool supported by the carriage for movement over the work support.

3. A machine of the character described including a support, a substantially horizontal platform on the upper end of the support, a work support on the platform, a frame having adjustable support on the platform and including laterally spaced brackets, a guide rail having ends carried by the brackets, a tubular rail member, eccentric supporting ends of the tubular rail member on the brackets, a rod extending coaxially within the tubular rail member and having ends connecting the eccentrics, a setscrew carried by the tubular rail member and having its inner end bearing upon the rod to curve the tubular rail member, a carriage having movable support on the guide rail, a tool carrying arm on the carriage, and a gauge member having rolling support on the tubular rail member and having connection with the arm to support said tool over the work support.

4. A machine of the character described including an upright support, a substantially horizontal platform on the upper end of the support, spaced guides extending across the platform, a carrier movable along the guides, work supports on the platform at opposite ends of the guides, a frame, a guide rail carried by the frame transversely of the guides on the platform, a motor carriage movable along the guide rail, an arm projecting from the motor carriage, a grinding wheel on said arm, a tubular guide member carried by the frame in spaced parallel relation with the guide rail, a rod coaxially supported in the tubular guide member, a set screw carried by the tubular guide member and having bearing contact on the rod to effect curving of the tubular guide member, a gauge member movable along the tubular guide member and having connection with said arm whereby the tubular guide member cooperates with the guide rail in supporting the grinding wheel relatively to said work support, and means rotatably mounting the said frame on the carrier for turning the frame on said carrier to position the grinding wheel over the other of said work supports.
